(57) **CLAIM**

The ornamental design for a door figurine, as shown and described.

DESCRIPTION

FIG. 1 is a perspective view of a door figurine in accordance with the invention;

FIG. 2 is a front elevation view of the door figurine shown in FIG. 1;

FIG. 3 is a rear elevation view of the door figurine shown in FIG. 1;

FIG. 4 is a left side elevation view of the door figurine shown in FIG. 1;

FIG. 5 is a right side elevation view of the door figurine shown in FIG. 1;

FIG. 6 is a top plan view of the door figurine shown in FIG. 1; and,

FIG. 7 is a bottom plan view of the door figurine shown in FIG. 1.

The dashed lines in FIGS. 1, 2, 4, 5, and 6 are included for the purpose of illustrating portions of the door figurine that form no part of the claimed design.
